DESIGN FOR A CHAIR

Willard H. Bond, Jr., East Grand Rapids, Mich.,
assignor to American Seating Company, Grand
Rapids, Mich., a corporation of New Jersey

Application June 20, 1936, Serial No. 63,405

Term of patent 7 years

To whom it may concern:

Be it known that I, Willard H. Bond, Jr., a citizen of the United States, residing at East Grand Rapids, in the county of Kent and State of Michigan, have invented a new, original, and ornamental Design for a Chair, of which the following is a specification, reference being had to the accompanying drawing, forming a part thereof, in which:—

The figure is a perspective view of a chair, the

distinguishing, essential and dominating feature or characteristic of the design being the end standards of the chair shown in full lines, the form and contour of the back and seat being shown in dotted lines and indicating unimportant features of the design.

I claim:

The ornamental design for a chair as shown and described.
